UNITED STATES PATENT OFFICE.

OLIVER SLAGLE, OF MONMOUTH, ILLINOIS, ASSIGNOR OF ONE-HALF TO
E. P. CLARK AND M. S. BALDWIN, OF SAME PLACE.

BUGGY-TOP.

SPECIFICATION forming part of Letters Patent No. 379,546, dated March 13, 1888.

Application filed November 22, 1887. Serial No. 255,921. (No model.)

To all whom it may concern:

Be it known that I, OLIVER SLAGLE, of Monmouth, in the county of Warren and State of Illinois, have invented certain new and useful Improvements in Buggy Sun-Shades and Storm-Protectors; and I do declare the following to be a full, clear, and exact description of the invention, such as will enable others skilled in the art to which it appertains to make and use the same.

The object of my invention is to provide a device which may be readily applied to the ordinary top buggy in common use, for the purpose of excluding sun from the sides and rear of the same in fair weather, which at the same time is adapted to be easily closed when the weather is stormy to exclude wind or rain.

The advantages of a top buggy closed at its sides and rear are thus secured when desired, and, on the other hand, in the first-mentioned position the device permits, while perfectly excluding the sun, a free circulation of air through the buggy from the sides and rear, and practically unobstructed views of the surrounding country.

The device comprises, essentially, a series of pivoted slates carried by a frame, which is conveniently attachable to or detachable from the ordinary buggy-top, and devices whereby the slates may be turned into either a horizontal or substantially vertical position and there secured.

In order to enable my invention to be clearly understood, I have shown in the accompanying drawings a means for carrying the same into effect.

In said drawings, Figure 1 is a perspective view of a top buggy having my invention applied thereto. Fig. 2 is a perspective view of a shade and protector detached embodying my invention. Fig. 3 is a view of the rear shade. Figs. 4 and 5 are detail views.

Referring to the drawings, A indicates the buggy-top of the usual construction, supported by the bows B, which latter are pivoted at their lower converging ends to the knobs or brackets b in the ordinary manner.

C indicates the toggle-braces by which the top is supported in its distended and upright position.

D is a rod or slat, which may be faced with

leather, as shown, the flap d of which covers the space above the next slat below, adapted to be secured in a horizontal position at the side of the buggy-top along the lower edge of its permanent covering, the upper edge of the slat being inserted beneath the flap a of said covering and its lower edge being supported and retained by the usual knobs or buttons, which are intended to hold the ordinary leather side curtains and which are fastened rigidly to the frame-work of the top. Similar buttons also form a convenient means for the attachment of the upper slat of the rear shade through the medium of strips of leather secured to said slat and provided with button-holes. I prefer that the buttons for the rear shade shall be on the outside and on top of the rear buggy-bow in order that when the top is lowered the strips of leather may not slip off of said buttons. The supports for the ends of the slats which form the shade are suspended from the top slat, D. In the construction shown these supports E are made of flexible material, such as a strip of leather or a stout tape, which makes a cheap and light device, and also enables the shade when removed from the buggy-top to be rolled up into a small compass. The lower ends of the supports E are secured to the lower portion of the top frame in any suitable manner. As said frame is usually provided with rigid buttons, already referred to, I prefer to utilize them or the knob b for this purpose. To prevent looseness or sagging of the shade, however, and give elasticity to the structure, the lower ends of said supports E are not secured directly to the buttons, but are provided with springs e, adapted when stretched to be connected with said buttons or with the knobs b. In the construction shown said springs are connected by a short cord or chain, e', of adjustable length, which may be looped under the knobs b, thus conveniently securing both springs by one motion.

F indicates the slats forming the main body of the shade. In order to provide for the pivotal movement of these slats, they each have at the ends short pins or pivots f, which pass through holes in the supports E and have at their outer ends washers or large heads f', to prevent said ends from being drawn through the flexible material of the support. The ma-

terial of the slats F, which will ordinarily be wood, is very thin and light, and in order to prevent the slats from being split by said pins I prefer to provide them at their ends with 5 binding or clamping pieces f^2 of tin or other suitable metal. It will thus be seen that each of the slats F is free to turn upon horizontal pivots and to take either a horizontal or a substantially vertical position.

10 The slats are connected so as to be operated simultaneously by means of a strip, g, of flexible material, which is hinged or loosely attached in any suitable manner to the edges of the slats.

15 The slats may be opened or placed in a horizontal position by means of a pull upon the upper end of the strip g, and may be closed by drawing the lower end of said strip downward. I prefer, however, that the former of 20 these movements shall be automatic and shall occur whenever the lower end of said strip shall be released. I therefore attach to the upper end of the strip a spring, g', and connect the upper end of the spring with the slat D or 25 other suitable fixed support. When, therefore, the strip g is not secured at its lower end, the slats F will be horizontal and open, so as to exclude the sun and permit free circulation of air and a practically unobstructed view, and 30 when it is desired to close the slats to keep out wind or rain the strip g will be drawn downward, the spring g' yielding for this purpose, and secured to the knob b or other fixed point of attachment in any suitable manner. In the 35 drawings said strip is shown as provided with a chain, g'', for this purpose.

The springs herein referred to may be either of metal or rubber. The sides of buggy-tops are usually of substantially triangular form. 40 The slats F, composing the side shades, will not therefore be all of the same length, but will decrease in longitudinal dimension from the top toward the bottom, as shown. Moreover, I prefer that the shades shall not occupy 45 the whole space at the side of the buggy-top, but that the rear portion of said space behind the rearmost of the bows B shall not be covered by any portion of the slats F. This space may be inclosed by a piece of flexible 50 material, H, of proper shape, which may be secured either to the buggy-top or to the shade, or to both. By thus leaving said space unoccupied by the rigid slats F, I am enabled to partly close the buggy-top when desired.

55 The rear shade will be composed of similar parts to those of which the side shades consist. The shape of the shade as a whole will, however, be different, and, if desired, the shade may be arranged to be closed by a spring 60 at the lower end of its strip g, and opened by pulling upon the upper end of the strip. The rear shade, moreover, instead of being secured at its lower end to the knobs b, will be attached to the buttons hereinbefore referred to.

65 In order to prevent a lateral flapping of the shade, I prefer to provide it with additional

fastening devices intermediate between its top and bottom. In the construction shown these devices consist of elastic bands i, which are attached at one end to the strips E, and are 70 provided at the other end with hooks i'. These bands are fastened so as to secure the shade by passing them around the rear and the front bows, B, respectively, and catching the hooks i' into eyes j, with which the strips 75 E are provided for this purpose.

The operation of my invention has been sufficiently indicated in the description of its construction and uses.

Having thus described my invention, what I 80 claim, and desire to secure by Letters Patent of the United States, is—

1. In a top-buggy shade, the combination, with a supporting-frame having a stiff top strip or slat, D, adapted to be held by the curtain-buttons of the ordinary buggy-top, of a series of slats loosely attached to said frame and adapted to turn, as described, and a means for securing said slats in either position.

2. In a top-buggy shade, the combination of 90 a supporting-frame, a series of slats loosely attached thereto and adapted to turn, as described, and springs connected with said frame for securing the latter elastically to the buggy-top.

3. In a top-buggy shade, the combination of 95 a supporting-frame adapted to be secured to the buggy-top, and having side strips of flexible material, and a series of slats loosely attached to said strips and adapted to be turned, substantially as described.

4. In a top-buggy shade, the combination of a supporting-frame adapted to be secured to the buggy-top, a series of slats loosely attached thereto and adapted to turn, a strip 105 connected with the said slats for turning the same, a spring secured to one end of said strip for drawing the same in one direction, and a securing device for holding the strip when drawn in the other direction against the 110 tension of the spring.

5. In combination with a buggy-top, a shade consisting of a supporting-frame, springs elastically connecting the frame to said top, and a series of slats mounted in said frame, 115 substantially as and for the purpose set forth.

6. A top-buggy shade consisting of a series of slats, and a supporting-frame carrying said slats and provided with holes or loops adapted in their position for the ready attachment of 120 the shade to the buttons of the buggy-top, substantially as set forth.

7. A top-buggy shade consisting of a supporting-frame adapted to be secured to the buggy-top, and a series of slats decreasing in 125 length from top to bottom of the series to fit the side of a buggy-top and permit the latter to be partly lowered, substantially as set forth.

8. In a top-buggy shade, the combination, with a supporting-frame, and a series of slats 130 carried thereby of decreasing length, as described, of a supplemental shade piece of flexi-

ble material, whereby the space at the rear of the slats at the side of the buggy-top may be closed and the partial lowering of said top also permitted.

5 9. In a top-buggy shade, the combination of a supporting-frame of substantially triangular shape adapted to be secured to the buggy-top, a tapering series of slats mounted in said frame, a spring secured to the lower end 10 of one of the side strips of the frame, and a

flexible loop secured to the lower end of said spring and connected at its other end immediately or mediately with the lower end of the other side strip, whereby the lower ends of said strips may be connected elastically 15 with the buggy-frame.

OLIVER SLAGLE.

In presence of—

SAM. S. HALLAM,

GEORGE E. EARP.
